UNITED STATES PATENT OFFICE.

GEORGE P. CARROLL, OF BRIDGEPORT, CONNECTICUT, AND FRANK N. ROEHRICH, OF JERSEY CITY, NEW JERSEY; SAID ROEHRICH ASSIGNOR TO SAID CARROLL.

AUTOMATIC EXPANSION-VALVE.

1,137,051.

Specification of Letters Patent. Patented Apr. 27, 1915.

Application filed February 9, 1910. Serial No. 542,870.

To all whom it may concern:

Be it known that we, GEORGE P. CARROLL and FRANK N. ROEHRICH, citizens of the United States, and residents, respectively, of 5 Bridgeport, Fairfield county, State of Connecticut, and of Jersey City, Hudson county, State of New Jersey, have invented a new and useful Automatic Expansion-Valve, of which the following is a specification.

10 Our invention relates in general to improvements in valves such as permit fluid to pass from one chamber to another chamber until checked or stopped by some device connected therewith.

15 The purpose of our invention is to construct a valve with a pocketless downward course from its inlet to its outlet; to make all interior parts readily accessible for repairs or interchanging without breaking any 20 pipe connections; to make possible a variation of capacity within wide limits by the interchange of a small minor part; and to provide a simple and effective valve guide. There are also detail improvements of construction as will appear. The means employed for accomplishing these ends are disclosed in the accompanying drawings and in the description relating thereto.

25 In the drawings Figure 1 is a vertical section of our invention, with connections, through the line 1—1 of Fig. 6, looking toward the left and with some minor parts in elevation. Fig. 2 is a front elevation of a support and its contained valve and connected parts. Fig. 3 is a plan view and Fig. 4 is a left end elevation of the same construction. Fig. 5 is a much enlarged front elevation of a seat piece, with certain adjacent parts in vertical section. Fig. 6 is a vertical 30 section through the line 6—6 of Fig. 1, looking toward the left and with some minor parts in elevation. Fig. 7 is a partial broken plan view and a partial view with some of the superstructure removed along the line 7—7 of Fig. 1. Fig. 8 is a partial view and a partial horizontal section of the valve through the line 8—8 of Fig. 1, looking 35 upward. Fig. 9 is a partial view and a partial horizontal section of the valve through the line 9—9 of Fig. 1, looking upward. Fig. 10 is a partial plan view and a partial horizontal section of the valve through the line 10—10 of Fig. 1, looking 40 downward.

45 A main casing 1 has connected to its inlet

face 2 by means of a two piece union 3, containing a lead gasket 4, a liquid pipe 5, leading from a reservoir, not shown; and it has connected to its outlet face 6 by means of a two piece union 7, containing a lead gasket 8, the inlet end of an expansion coil 9.

From the center of the face 2 a passage 10 leads into a plate chamber 11, having its main part in the form of a vertical cylinder at its top extending up into the casing 1, 65 considerably above the upper line of the passage 10 and the intervening part of the chamber, and underneath opening through the bottom wall of the casing. Extending upward in the casing above the cylindrical part of the chamber 11 is a small cylindrical recess 12. The part of the chamber 11 in front of its main cylindrical part has its top line horizontal with the upper line of the passage 10, enlarged somewhat to 70 the right and left and drops rapidly downward from below the passage 10 so as to leave considerable space in front of the main cylindrical part. In the wall of the under side of the casing 1, where the chamber 11 opens through, is an annular gasket recess 13 of slightly larger diameter. A small intermediate passage 14 leads directly from the cylindrical part of the chamber 11, a little above the recess 13 75 and opposite the passage 10, and slopes slightly downward. In axial alinement with the passage 14, and on the same side with the passage 10, is a threaded plug opening 15. The passage 14 may be drilled in 80 the casing 1 for the proper distance, as will appear, by a drill inserted through the opening 15. In such case the opening 15 is subsequently closed by a threaded plug 16, either litharge and glycerin being used to make a 85 tight joint or the plug being autogenously welded into the opening.

90 Fitting into the cylindrical part of the chamber 11 from beneath through the opening in the casing 1, is a cylindrical frame 100 17 having a rectangular passage 18 through it, at the back of the same area as the final area of the part of the chamber 11 in front of the main cylindrical part, and with a rectangular recess 19 extending from the front 95 of the frame to a line a little to the right of the vertical center of the frame as seen in Fig. 1. In the recess 19 and upon the rectangular ledge formed by this construction is placed a foraminous plate 20, pref-

erably of steel wire cloth say of forty or fifty mesh. The plate 20 occupies the recess 19 and is slightly larger than the transverse areas of the part of the chamber 11, in front of its main cylindrical part, and of the passage 18. Fitting snugly into the recess 19 and holding the plate 20 in place is a stopper 21, having a rectangular passage through it registering in front with the front part of the chamber 11 and in back with the passage 18. The bottom lines of the passage through the stopper 21 and of the passage 18 are in the same horizontal line as the inlet end of the passage 14. Secured into the top of the frame 17 is a pin 22 occupying the recess 12 and thus keeping the frame from turning in such a way as to interfere with a free passage through the stopper 21; the plate 20 and the passage 18 into the passage 14. The bottom end of the frame 17 is of less diameter than its main part, so as to form an annular recess registering with the recess 13 when the frame is inserted in place. At the lowest end of the frame 17 is an extension 22 with a hole through it. The frame 17 makes a close fit in the cylindrical part of the chamber 11; but it can be easily removed by inserting a hook or wire through the hole of the extension 22. After the frame 17 has been inserted upward into its place a lead gasket 23 is placed in the recess 13 and the corresponding recess of the frame; and the entire removable structure is held in place by a threaded cap 24, having an internal nut in its under end for screwing the cap into the opening in the casing 1 below the recess 13, the lower part of the opening being correspondingly threaded for this purpose. By this means the gasket 23 is compressed and a gas tight joint is secured.

From beneath upward into the inner and lower end of the passage 14 is drilled a small vertical passage 25. Beneath and in axial alinement with the passage 25 is a slight recess 26; and beneath and in axial alinement with them is a larger and much longer recess 27, opening downward into a chamber 28 in the casing 1, which chamber there has a horizontal inner wall. Inserted up into the recesses 26 and 27 is a seat piece 29, best shown in enlarged form in Fig. 5, having through its vertical center a small passage 30 not greater in diameter than the passage 25 and terminating at its lower end in a flat horizontal valve seat 31 within the chamber 28. The upper part of the piece 29 within the recess 27 is of the same diameter as the part of the piece within the recess 26 so as to form a shoulder, upon which is placed a lead or pure rubber gasket 32. The part of the recess 27, below where the gasket 32 is to be placed, is threaded; and the wide part of the piece 29 within the recess 27 is correspondingly threaded. The part

of the piece 29 within the chamber 28 and above the seat 31 is in the form of a square nut. By this construction, after the gasket 32 has been placed around the shoulder of the piece 29, the piece is screwed into the recess 27 so as to compress the gasket and thus to prevent the passage of fluid other than through the passage 30.

The main part of the chamber 28 below the horizontal plane at the bottom end of the recess 27 is vertically cylindrical. The minor part of the chamber 28 above this horizontal plane is also vertically cylindrical, but is of less diameter and is eccentric as to the lower part so as to form the horizontal inner wall above referred to. As best seen in Fig. 9, this inner wall is crescent shaped except as pierced for the piece 29. Some distance below the recess 27 the main part of the chamber 28 is of somewhat enlarged diameter so as to form an internally threaded recess 33. From the lower part of the recess 33 opposite the passage 25 emerges an outlet passage 34 through an externally threaded hub 35 and ending in the outlet face 6 so as to register with the expansion coil 9. The upper part of the chamber 28 has around its top a flat annular rim 36. Above and outside of the rim 36 is a shallow annular depression 37 in the casing 1, depressed just outside of the rim and at its circumference of such depth as to be in the same horizontal plane as the top of the rim. In the casing 1 outside of the depression 37 are a number, say eight, of threaded bolt holes 38. The distance of the depression 37 above the passage 14 is only sufficient to insure a strong and safe construction. Two of these bolt holes are equally distant on each side of the vertical center of the passage 14.

A gasket 39, preferably of lead, fits into the outer edge of the depression 37. Over the gasket 39 is placed an imperforate diaphragm 40, slightly corrugated between the gasket and a circle about half way to the center of the diaphragm. Preferably the diaphragm is made of very thin vanadium steel for use with ammonia and of phosphor bronze for use with carbon dioxid. Above the diaphragm 40 is placed a rigid annular limiting piece 41, near its circumference resting on the diaphragm and spaced more and more away therefrom toward its own annular center. This piece is corrugated so as to register with the corrugations of the diaphragm 40 and has quite a number of escape holes 42, so that, whenever the diaphragm is forced upward, any fluid between the diaphragm and the piece can pass through these holes. In Fig. 1, when all the movable parts of the valve are in the positions there shown, the distance of the annular center of the piece 41 from the diaphragm is somewhat exaggerated for the sake of clearness of illustration. Over and around the circum-

ference of the piece 41 is placed another gasket 43.

A foot 44 has, inside the circular opening in the piece 41 and resting upon the part of the diaphragm 40 within its corrugated part, a flanged extension with a flat under surface. Above its extension the foot 44 is hollow and outwardly cylindrical, with radial escape holes 45 in the cylindrical part just above the extension, having functions similar to those of the holes 42. The foot 44 also has within its cylindrical part an annular pocket for the support of a heavy helical compression spring 46. At its top the spring 46 abuts against the annular seat of a head 47, having on top a concave recess. An upper casing 48 fits over the head 47 and the spring 46, surrounds and guides the cylindrical part of the foot 44, presses down the gasket 43 and is secured to the casing 1 by bolts 49 which screw into the holes 38. The casing 48 is sufficiently spaced away from the piece 41 so as to permit of fluid passing from the holes 42 through the holes 45; and it has just above the extension of the foot 44 an annular recess 50 in which the extension may reciprocate for a short distance only. Through a threaded opening in the center and top of the casing 48 passes an adjusting nut 51, having at its exterior top a wrench section and having a convex lower end resting in the concave recess of the head 47. The convex end of the nut 51 has a little less radius of convexity than is the radius of concavity of the recess in the head 47. Consequently the nut 51 can bear upon the head 47 and be freely rotated in its recess without rotating the head. The nut 51 also has a left hand thread. Around the outside of the top of the casing 48 is an annular recess containing a lead gasket 52. The extreme top of the casing 48 is externally threaded. Fitting over the wrench section of the nut 51 and threaded on to the top of the casing 48 so as to compress the gasket 52 is a cap 53, having a nut at its top.

A small vertical passage 54 extends upward from near the inner end of the passage 34 through the outer wall of the casing 1 to the depression 37 just outside of the rim 36. Rigidly fitting in both the upper and lower parts of the chamber 28 is a support 55, extending up almost to the top of the rim 36, but preventing from working any higher by means of a flange abutting against the shoulder made by the upper end of the recess 33. The upper end of the support 55 within the upper part of the chamber 28 is in the shape of a cylindrical cup with a perforated bottom 56 near the line between the upper and lower parts of the chamber. Within the cup of the support 55 a light helical compression spring 57, abutting at its lower end against the bottom 56, continually thrusts the head of a

bolt 58 against the center of the under side of the diaphragm 40. The head of the bolt 58 makes an easy reciprocating fit in the cup of the support 55; and its shank passes through the perforation in the bottom 56, 70 is smooth within the perforation and upward to the head of the bolt, and is threaded at its lower end. Below the bottom 56, the remainder of the support has a bay shaped space, open at the part of its circumference under the piece 29 and having vertical guiding jaws near its vertical center, as best seen in Fig. 3. Threaded on to the shank of the bolt 58, making an easy reciprocating fit with the guiding jaws of the 80 support 55 and with its inner wall opposite to the opening in its bay shaped space, but spaced away from the walls of the bay shaped space and from the adjacent vertical wall of the chamber 28, is a valve 59, 85 having a shallow annular recess around the shank and carrying a flat plate 60 immediately under the seat 31. While the piece 29 is preferably of machine steel, the plate 60 is preferably of some other metal such as 90 nickel or tin. Lead is a little too soft for long usage. But it is also possible to use some alloy of lead and tin or of lead and antimony. On the under side of the valve 59 around the shank of the bolt 58 is an 95 annular hub, spaced away a little from the support 55. The bottom of the shank of the bolt 58 is slotted. A slotted lock nut 61 is threaded on to the lower end of the shank of the bolt 58 so as to bear against and to 100 be coextensive with the hub on the under side of the valve 59. A threaded and slotted ring 62 is screwed into the recess 33 so as to hold the support 55 in place without interfering with a free movement of its contained parts. The ring 62 at its slotted part is of a little less diameter than above where it is threaded. The bay shaped part of the support 55 is so much wider than the part of the valve under the piece 29 and there is 105 so much space between that part of the valve and the adjacent vertical wall of the chamber 28 that there is a free passage downward from the passage 30 on three sides of the valve to the bottom of the support 55; 110 and the ring 62 is enough above the passage 34 and has so wide an opening through it around the nut 61 that there is a free passage through the ring into the passage 34. The bottom of the casing 1 outside of the recess 33 has an annular groove containing 115 a lead gasket 63. A cap 64, having an internal nut, is screwed into the recess 33 with an external outside flange and an annular tongue in the flange compressing the gasket 63 so as to make a tight joint. The top surface of the cap 64 inside the recess 33 is in 120 the same horizontal plane as the bottom line of the passage 34. The bottom of the cap 64 is 125

In assembling the parts a piece 29 is 130

chosen that has a passage 30 of a diameter not greater than the diameter of the passage 25, it being also assumed that the passages leading to the passage 25 are not of less diameter than it is and the outlet passages are of sufficient capacity to carry off the fluid passing through the valve. But a piece 29 may be chosen with a passage 30 of as much less diameter than the passage 29 as may be desired. With such a range of choice the capacity of the valve can be varied within wide limits. And at any time after removing the valve 59, in the manner to be described, another piece 29 can be substituted, having a passage 30 of any desired diameter.

Before inserting the support 55 into the chamber 28 the spring 57 is put in place in the support and the valve 59 is inserted up into the support so as to bear against the bottom 56. The shank of the bolt 58 is then passed through the spring 57 and the bottom 56 and is then turned from above so as to project through the valve 59. Then the shank is further turned by means of a screw driver inserted into the slot at its lower end until the parts referred to are in substantially the position shown in Figs. 1 and 6. Then the nut 61 is screwed around the shank of the bolt 58 by means of a screw driver inserted in its slot until the nut bears against the valve 59. The support 55, containing the spring 57, the bolt 58, the valve 59, the plate 60 and the nut 61, is then inserted into the chamber 28 and is held in place by the ring 62, which is screwed in by means of a screw driver inserted into its slot. The cap 64 is then screwed into place. The strength of the spring 57 is such as to support the bolt 58, the valve 59, the plate 60 and the nut 61 under all conditions of operation.

After the casing 48 has been bolted over its contained parts, but before the nut 51 has been screwed into place, a little glycerin or heavy mineral oil may be poured in so as to cover the diaphragm 40 and thus to protect it from rusting. The nut 51 is then inserted and is turned lower or higher so as to increase or diminish, as may be desired, the thrust of the spring 46 upon the foot 44 and consequently to tend with greater or less force to depress the diaphragm 40 and the bolt 58. But under all circumstances, until there is sufficient counteracting fluid pressure on the under side of the diaphragm, the thrust of the spring 46 is sufficient to overcome the counter thrust of the spring 57 and, by depressing the bolt 58, to unseat the valve 59. Owing to the convex and concave bearing surfaces of the nut 51 and the head 47, the nut can be turned up or down without twisting the spring 46.

The method of operation is as follows: With the pipe 5 and the coil 9 as parts of a

refrigerating system, liquid ammonia, if that is the refrigerant used, passes through the pipe 5, the passage 10, the chamber 11, the stopper 21, the plate 20, the passage 18, the passage 14, the passage 25 and the passage 30, where it begins to vaporize. Most of the vaporizing ammonia rushes past the valve 59 down through the chamber 28, the recess 33 and the passage 34 into the coil 9. But a small portion of the vapor passes up through the passage 54 into the depression 37 so as to exert a tension on the diaphragm 40. Consequently the diaphragm tends to act on the foot 44 so as to compress the spring 46 and the spring 57 acts on the bolt 58 so as to tend to close the valve 59. The partial closing of the valve 59 throttles the flow of ammonia through the passage 30. And as vaporizing ammonia continues to be drawn off through the coil 9, the tension of vapor on the under side of the diaphragm 40 diminishes and the valve 59 tends to open a little more. The three forces of the spring 46, the spring 57 and the vapor on the under side of the diaphragm 40 soon produce an approximate equilibrium so that an approximately constant pressure is thereafter maintained in the coil 9. This pressure may be increased or diminished, as desired, by lowering or raising the nut 51.

As the diaphragm 40 reciprocates for the short distance necessary to close or open the valve 59, any superimposed glycerin or oil is free to surge back and forth through the holes 42 and 45. It occasionally happens, by accident, that the pressure in an expansion coil may equalize throughout the system, in which case a thin diaphragm in the expansion valve might be expanded beyond its limit of resiliency. In our construction such danger is made impossible of occurrence by three means, protecting the entire diaphragm 40. The recess 50 prevents the foot 44 from being thrust too far upward. The flat under surface of the foot 44 causes the center of the diaphragm 40 to lie flat against the foot at all times. And the limiting piece 41 prevents the corrugated part of the diaphragm from expanding out of shape under stress of excessive internal pressure. On the other hand the rim 36 prevents an excessive inward movement of the diaphragm 40, however tense the spring 46 may be. And since the foot 44 has an area such as to cover the entire rim 36, there can be no shearing strain on the diaphragm 40.

By reason of the bolt 58 being guided in the extreme top of the support 55 and of the valve 59 being guided, as before described, near the bottom of the support, it happens that, when the valve is seated, the plate 60 bears flat against its seat 31. By reason of the hub on the under side of the valve 59 and also of the nut 61 being spaced slightly away from the support 55, there is

no chance of binding at this point. If, at any time after the valve has been assembled, it is desired to adjust the longitudinal position of the valve, this can easily be done, 5 after unscrewing the cap 64 and the nut 61, by screwing the bolt 58 up or down by means of a screw driver inserted into its slot. So also upon unscrewing the ring 62, the support 55 and all its contained parts may be 10 readily taken out.

The entirely downward course from the face 2 to the face 6 eliminates all pockets and makes a valve that can be used with absorption refrigerating machines employing 15 water as the absorbent. It also is to be noted that the spring 57 is placed out of the course of the passing fluid and cannot be clogged by any freezing of entrained water or of the expanding fluid, if so liable. For 20 our valve is also well adapted for use as a reducing valve for liquefied carbonic acid gas. The freezing point of this substance is such a few degrees below its liquefying point under pressure that, if the liquefied 25 carbonic acid gas is allowed to escape through a small orifice into the atmosphere or into a chamber where the pressure is less than five and one-half atmospheres, the consequent vaporization of most of the liquid 30 will freeze a part of the escaping liquid and this frozen part may lodge in any convenient pocket and clog the passages. But the free downward course from the seat 31 into the coil 9 is pocketless and the spring 57 is 35 inaccessible.

What we have invented and what we desire to have protected by Letters Patent is expressed in claims as follows:

We claim:

40 1. In combination a chamber casing having an inlet, a valve seat around the inlet and an outlet, a valve within the chamber in said casing and adapted for seating on said seat, a diaphragm forming one wall of said chamber, a carrier separate from and bearing against said diaphragm and carrying said valve, a guide support guiding said carrier and valve near both extremes thereof, means tending to force said diaphragm outward and to seat said valve, and means tending to force said diaphragm inward and to unseat said valve and exerting greater force than said former means.

2. In combination a chamber casing having a valve seat, a valve adapted for seating on said seat, a diaphragm forming one wall of the chamber in said casing, means secured to said valve and operating when said diaphragm moves outward a certain distance to seat said valve, said valve being eccentric as to said means and longitudinally adjustable thereon, and means tending to force said diaphragm inward and to unseat said valve.

3. In combination a chamber casing having a valve seat, a valve adapted for seating

on said seat, a diaphragm forming one wall of the chamber in said casing, means secured to said valve and tending to force said diaphragm outward and to seat said valve, said valve being eccentric as to said means and longitudinally adjustable thereon, and means tending to force said diaphragm inward and to unseat said valve and exerting greater force than said former means. 70

4. In combination a chamber casing having a valve seat, a valve adapted for seating on said seat, a diaphragm forming one wall of the chamber in said casing, reciprocating means secured to said valve and operating when said diaphragm moves outward a certain distance to seat said valve, said valve being eccentric as to said means and longitudinally adjustable thereon, and means tending to force said diaphragm inward and to unseat said valve. 75

5. In combination a chamber casing having a valve seat, a valve adapted for seating on said seat, a diaphragm forming one wall of the chamber in said casing, reciprocating means secured to said valve and tending to force said diaphragm outward and to seat said valve, said valve being eccentric as to said means and longitudinally adjustable thereon, and means tending to force said diaphragm inward and to unseat said valve 95 and exerting greater force than said former means.

6. In combination a chamber casing having a valve seat, a valve adapted for seating on said seat, a diaphragm forming one wall of the chamber in said casing, a carrier secured to said valve separate from and bearing against said diaphragm, said valve being eccentric as to said carrier and longitudinally adjustable thereon, a spring tending to cause said carrier to seat said valve with an outward movement of said diaphragm, and means tending to force said diaphragm and carrier inward and to unseat said valve and exerting greater force than said spring. 105

7. In combination a chamber casing having a valve seat opening downward and an outlet below the seat, a valve adapted for seating on said seat, a diaphragm forming one wall of the chamber in said casing, a carrier secured to said valve separate from and bearing against said diaphragm, said valve being eccentric as to said carrier and longitudinally adjustable thereon, a spring above said outlet tending to cause said carrier to seat said valve with an outward movement of said diaphragm, and means tending to force said diaphragm and carrier inward and to unseat said valve and exerting greater force than said spring. 115

8. In combination a chamber casing containing a valve chamber partly of a smaller diameter and partly of a larger diameter, having a wall transverse to the axis of the chamber and adjacent to its part of smaller 120 diameter.

diameter, having a valve seat in said wall eccentric as to its part of smaller diameter and having a diaphragm chamber connected with the part of the valve chamber of 5 smaller diameter, a valve adapted for seating on said seat, a diaphragm forming one wall of said diaphragm chamber, means secured to said valve and tending to force said diaphragm outward and to seat said 10 valve, said valve being eccentric as to said means and longitudinally adjustable thereon, and means tending to force said diaphragm inward and to unseat said valve and exerting greater force than said former means.

15 9. In combination a chamber casing containing a valve chamber partly of a smaller diameter and partly of a larger diameter, having a wall transverse to the axis of the chamber and adjacent to its part of smaller 20 diameter, having a valve seat in said wall eccentric as to its part of smaller diameter and having a diaphragm chamber connected with the part of the valve chamber of smaller diameter, a valve adapted for seating 25 on said seat, a diaphragm forming one wall of said diaphragm chamber, a carrier secured to said valve separate from and bearing against said diaphragm, said valve being eccentric as to said carrier and longitudinally 30 adjustable thereon, a spring tending to cause said carrier to seat said valve with an outward movement of said diaphragm, and means tending to force said diaphragm and carrier inward and to unseat said valve and exerting greater force than said spring.

35 10. In combination a chamber casing containing a smaller guiding chamber and a connected larger guiding chamber, having a valve seat in the wall of the larger chamber 40 transverse to its longitudinal axis and adjacent to the smaller chamber and having a diaphragm chamber connected to the smaller chamber, a valve adapted for seating on said seat, a diaphragm forming one wall 45 of said diaphragm chamber, a carrier secured to said valve separate from and bearing against said diaphragm and guided in said guiding chambers, said valve being eccentric as to said carrier and longitudinally 50 adjustable thereon, means causing said carrier to move outward with an outward movement of said diaphragm and tending to seat said valve, and means forcing said diaphragm and carrier inward so as to unseat 55 said valve except when opposed by a predetermined fluid pressure on the inner side of the diaphragm.

60 11. In combination a chamber casing containing a smaller guiding chamber and a connected larger guiding chamber, having a valve seat in the wall of the larger guiding chamber transverse to its longitudinal axis and adjacent to the smaller chamber and having a diaphragm chamber connected

with the smaller chamber, a valve adapted for seating on said seat, a diaphragm forming one wall of said diaphragm chamber, a carrier secured to said valve separate from and bearing against said diaphragm and guided in said guiding chambers, said valve being eccentric as to said carrier, a spring tending to cause said carrier to seat said valve with an outward movement of said diaphragm, and means tending to force said diaphragm and carrier inward and to unseat said valve and exerting greater force than said spring.

12. In combination a chamber casing containing a smaller guiding chamber and a connected larger guiding chamber, having a valve seat in the wall of the larger chamber transverse to its longitudinal axis and adjacent to the smaller chamber and having a diaphragm chamber connected with the smaller chamber, a valve adapted for seating on said seat, a diaphragm forming one wall of said diaphragm chamber, a carrier secured to said valve separate from and bearing against said diaphragm and guided in said guiding chambers, said valve being eccentric as to said carrier and longitudinally adjustable thereon, a spring tending to cause said carrier to seat said valve with an outward movement of said diaphragm, and means tending to force said diaphragm and carrier inward and to unseat said valve and exerting greater force than said spring.

13. In combination a casing containing a diaphragm chamber, a spring chamber opening from the diaphragm chamber and a valve chamber opening from the spring chamber and having a valve seat in the valve chamber eccentric as to the axis of the spring chamber and an outlet below the spring chamber, a diaphragm forming the wall of said diaphragm chamber opposite the opening into said spring chamber, a valve in said valve chamber adapted for seating on said seat, a carrier extending from said valve chamber into said diaphragm chamber, separate from and bearing against said diaphragm, said valve being secured to said carrier and being longitudinally adjustable thereon, a spring in said spring chamber thrusting said carrier against said diaphragm and thereby tending to seat said valve with an outward movement of the diaphragm, and means for forcing said diaphragm and carrier inward so as to unseat said valve.

14. In combination a casing containing a diaphragm chamber, a spring chamber opening from the diaphragm chamber and a valve chamber opening from the spring chamber and having a valve seat in the valve chamber eccentric as to the axis of the spring chamber and an outlet below the spring chamber, a diaphragm forming the wall of said diaphragm chamber opposite

the opening into said spring chamber, a valve in said valve chamber adapted for seating on said seat and having an extension with a threaded opening therein, a carrier extending from said valve chamber into said diaphragm chamber, having a threaded end occupying said threaded opening and having a head separate from and bearing against said diaphragm, a spring in said 10 spring chamber thrusting said head against said diaphragm and thereby tending to seat said valve with an outward movement of the diaphragm, and means for forcing said diaphragm and head inward so as to unseat 15 said valve.

15. In combination a casing containing a diaphragm chamber, a spring chamber opening from the diaphragm chamber and a valve chamber opening from the spring 20 chamber and having a valve seat in the valve chamber and a pressure transmitting passage between the diaphragm chamber and the valve chamber, a diaphragm forming the wall of said diaphragm chamber opposite the opening into said spring chamber, a valve in said valve chamber adapted for seating on said seat, a carrier extending from said valve chamber into said diaphragm chamber, making a reciprocating 25 fit in the opening between said spring chamber and said valve chamber and bearing against said diaphragm and separate therefrom, said valve being secured to said carrier and being longitudinally adjustable thereon, 30 a spring in said spring chamber thrusting said carrier against said diaphragm and thereby tending to seat said valve with an outward movement of the diaphragm, and means for forcing said diaphragm and carrier inward so as to unseat said valve.

16. In combination a casing containing a diaphragm chamber, a spring chamber opening from the diaphragm chamber and a valve chamber opening from the spring 45 chamber and having a valve seat in the valve chamber and a pressure transmitting passage between the diaphragm chamber and the valve chamber, a diaphragm forming the wall of said diaphragm chamber opposite the opening into said spring chamber, a valve in said valve chamber adapted for seating on said seat and having an extension with a threaded opening therein, a carrier extending from said valve chamber into said 50 diaphragm chamber, having a threaded end occupying said threaded opening, making a reciprocating fit in the opening between said spring chamber and said valve chamber and having a head separate from and bearing 55 against said diaphragm, a spring in said spring chamber thrusting said head against said diaphragm and thereby tending to seat said valve with an outward movement of the diaphragm, and means for forcing said dia-

phragm and head inward so as to unseat 65 said valve.

17. In combination a casing having an inlet passage terminating in a valve seat and having a chamber beyond the seat, a diaphragm forming one wall of said chamber, a valve 70 adapted for seating on said seat, a carrier bearing against said diaphragm and carrying said valve, a spring thrusting said carrier against said diaphragm and thereby tending to seat said valve with an outward 75 movement of the diaphragm, a removable support in said chamber supporting said spring, means for forcing said diaphragm and carrier inward so as to unseat said valve, and a detachable section normally 80 closing said chamber and whereby access may be had to said valve, carrier, spring and support.

18. In combination a casing having an inlet passage terminating in an inlet recess 85 and having a chamber beyond the recess, a diaphragm forming one wall of said chamber, a seat piece detachably secured within said recess and having a passage registering with said inlet passage and terminating in a 90 valve seat within said chamber, a valve adapted for seating on said seat, a carrier bearing against said diaphragm and carrying said valve, a spring thrusting said carrier against said diaphragm and thereby 95 tending to seat said valve with an outward movement of the diaphragm, a removable support in said chamber supporting said spring, means for forcing said diaphragm and carrier inward so as to unseat said valve, 100 and a detachable section normally closing said chamber and whereby access may be had to said piece, valve, carrier, spring and support.

19. In combination a casing containing a 105 diaphragm chamber, a spring chamber opening from the diaphragm chamber and a valve chamber opening from the spring chamber and having a valve seat in the valve chamber eccentric as to the axis of the 110 spring chamber and an outlet below the spring chamber, a diaphragm forming the wall of said diaphragm chamber opposite the opening into said spring chamber, a valve in said valve chamber adapted for 115 seating on said seat, a carrier extending from said valve chamber into said diaphragm chamber, separate from and bearing against said diaphragm, said valve being secured to said carrier and being longitudinally adjustable thereon, a spring in said spring chamber thrusting said carrier against said diaphragm and thereby tending to seat said 120 valve with an outward movement of the diaphragm, and means tending to force said 125 diaphragm and carrier inward and to unseat said valve and exerting greater force than said spring.

20. In combination a casing containing a diaphragm chamber, a spring chamber opening from the diaphragm chamber and a valve chamber opening from the spring chamber and having a valve seat in the valve chamber, eccentric as to the axis of the spring chamber and an outlet below the spring chamber, a diaphragm forming the wall of said diaphragm chamber opposite the opening into said spring chamber, a valve in said valve chamber adapted for seating on said seat and having an extension with a threaded opening therein, a carrier extending from said valve chamber into said diaphragm chamber, having a threaded end occupying said threaded opening and having a head separate from and bearing against said diaphragm, a spring in said spring chamber thrusting said head against said diaphragm and thereby tending to seat said valve with an outward movement of the diaphragm, and means tending to force said diaphragm and head inward and to unseat said valve and exerting greater force than said spring.

21. In combination a casing containing a diaphragm chamber, a spring chamber opening from the diaphragm chamber and a valve chamber opening from the spring chamber and having a valve seat in the valve chamber and a pressure transmitting passage between the diaphragm chamber and the valve chamber, a diaphragm forming the wall of said diaphragm chamber opposite the opening into said spring chamber, a valve in said valve chamber adapted for seating on said seat, a carrier extending from said valve chamber into said diaphragm chamber, making a reciprocating fit in the opening between said spring chamber and said valve chamber and bearing against said diaphragm and separate therefrom, said valve being secured to said carrier and being longitudinally adjustable thereon, a spring in said spring chamber thrusting said carrier against said diaphragm and thereby tending to seat said valve with an outward movement of the diaphragm, and means tending to force said diaphragm and carrier inward and to unseat said valve and exerting greater force than said spring.

22. In combination a casing containing a diaphragm chamber, a spring chamber opening from the diaphragm chamber and a valve chamber opening from the spring chamber and having a valve seat in the valve chamber and a pressure transmitting passage between the diaphragm chamber and the valve chamber, a diaphragm forming the wall of said diaphragm chamber opposite the opening into said spring chamber, a valve in said valve chamber adapted for seating on said seat and having an ex-

tension with a threaded opening therein, a carrier extending from said valve chamber into said diaphragm chamber, having a threaded end occupying said threaded opening, making a reciprocating fit in the opening between said spring chamber and said valve chamber and having a head separate from and bearing against said diaphragm, a spring in said spring chamber thrusting said head against said diaphragm and thereby tending to seat said valve with an outward movement of the diaphragm, and means tending to force said diaphragm and head inward and to unseat said valve and exerting greater force than said spring.

23. In combination a casing having an inlet passage terminating in a valve seat and having a chamber beyond the seat, a diaphragm forming one wall of said chamber, a valve adapted for seating on said seat, a carrier bearing against said diaphragm and carrying said valve, a spring thrusting said carrier against said diaphragm and thereby tending to seat said valve with an outward movement of the diaphragm, a removable support in said chamber supporting said spring, means tending to force said diaphragm and carrier inward and to unseat said valve and exerting greater force than said spring, and a detachable section normally closing said chamber and whereby access may be had to said valve, carrier, spring and support.

24. In combination a chamber casing having an inlet passage terminating in an inlet recess, a seat piece detachably secured within said recess, having a passage registering with said inlet passage and having around its inner termination a valve seat within the chamber of said casing, a valve adapted for seating on said seat, a diaphragm forming one wall of said chamber, a carrier bearing against said diaphragm and carrying said valve, a removable support in said chamber supporting said carrier, a spring resting in said support and acting upon said carrier and thereby tending to force said diaphragm outward and to seat said valve, and means forcing said diaphragm and carrier inward so as to unseat said valve except when opposed by a predetermined fluid pressure on the inner side of the diaphragm.

25. In combination a chamber casing having an inlet passage terminating in an inlet recess, a seat piece detachably secured within said recess, having a passage registering with said inlet passage and having around its inner termination a valve seat within the chamber of said casing, a valve adapted for seating on said seat, a diaphragm forming one wall of said chamber, a carrier bearing against said diaphragm and carrying said valve, a removable support

in said chamber supporting said carrier, a spring resting in said support and acting upon said carrier and thereby tending to force said diaphragm outward and to seat said valve, means forcing said diaphragm and carrier inward so as to unseat said valve except when opposed by a predetermined fluid pressure on the inner side of the diaphragm, and a detachable section in

said casing wall whereby access may be had 10 to said piece, valve, carrier, support and spring.
